(57) **CLAIM**

The ornamental design for a car gear shift knob, as shown and described.

DESCRIPTION

FIG. 1 is a front view of the car gear shift knob showing my new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a front, left, top perspective view thereof; and,

FIG. 8 is a rear, right, bottom perspective view thereof.

The broken lines in the figures illustrate the portions of the car gear shift knob that form no part of the claimed design.
